UNITED STATES PATENT OFFICE

CHARLES S. BURTON, OF OAK PARK, ILLINOIS

VACUUM-OPERATED FUEL-FEEDING APPARATUS

Application filed October 24, 1929. Serial No. 402,205.

A purpose, among others, of this invention is to provide an improved construction of vacuum fuel feeding device adapted for supplying an internal combustion engine, in which suction derived from the engine intake manifold may be employed for lifting the fuel from a low level main supply tank to the vacuum chamber at intervals alternating with intervals in which the fuel is delivered from the vacuum chamber into a fuel accumulating chamber, without interrupting the flow through the suction line to the engine intake manifold, but instead, shifting the communication so that during the lifting phase of the cycle of the device, the air and vapor drawn into the intake manifold shall be taken from above the fuel in the vacuum chamber, and in the delivering phase of the cycle, the air and vapor drawn into the manifold shall be taken from above the liquid in the accumulating chamber; whereby the effect on the fuel mixture in the intake manifold will not be materially different in the alternating phases of the crank cycle.

Another purpose of the present invention is to provide a construction operating in a manner above stated, in which the access of atmospheric pressure to the vacuum chamber during the emptying phase of the device, may be as much freer than the access of suction during the feeding phase as necessary in order that discharge of fuel from the vacuum chamber in the emptying phase may be prompt and free, not being retarded by the restricted access of air which is due to having access of atmosphere and suction equally restricted.

The invention consists in the elements and features of construction shown and described as indicated in the claims.

In the drawings:

Figure 1 is a vertical section of a vacuum tank embodying this invention broken away at the middle part of the height to condense the view.

Figure 2 is a section at the line 2—2 on Figure 1.

Figure 3 is a detail section at the line 3—3 on Figure 1.

Figure 4 is a section at the line 4—4 on Figure 3.

Referring to the drawings in detail: The accumulating chamber is indicated at A; the shell which constitutes the vacuum chamber is indicated at B, having the usual valve-controlled discharge fitting seen at C for delivering the fuel into the accumulating chamber from which it may flow by gravity to the carburetor as indicated by the discharge connection, D.

The vacuum chamber body is flanged outwardly, as seen at 20, for securement to said body of the top plate, 21, which is made liquid-tight by a gasket, 22, interposed on the flange, 21, and clamped by screws, 23. The vacuum chamber is supported in the accumulating chamber by an annular shoulder element, E, comprising an annulus, 25, having inner diameter corresponding to the outer diameter of the vacuum chamber, B, and outer diameter corresponding approximately to the diameter of the vacuum chamber flange and top plate, said annulus having three angle lugs, 26, 26, 26, one hundred and twenty degrees (120°) apart dimensioned for fitting within the accumulating chamber with their down-turned end portions abutting on the inner wall of the latter. This annular shoulder member is permanently mounted in the accumulating chamber by soldering or spot-welding the lugs, 26, to the wall of the chamber; and the vacuum chamber is arranged to be inserted through the open center of the annulus, 25, and supported by lodgement of the flange, 20, on said annulus, 25.

The vacuum chamber is furnished with a fuel supply connection consisting of an elbow fitting, 28, which is screwed tight into a bushing, 29, mounted permanently liquid-tight in the top plate, 21, and carrying a strainer, 30, in a familiar manner of such constructions.

Beside the fuel inlet port, 31, at which the elbow fitting, 28, is connected, and the fuel discharge port, 32, at which the discharge fitting, C, is connected, the vacuum chamber has a third port, 33, in the top plate, this port being conveniently formed in a

small steel disk, 34, which is applied and secured fluid-tight on the top of the plate, 21, over an aperture, 35, made in the top plate, of any convenient size, which will be 5 completely covered by the steel plate except as to the port, 33, of said plate. This method of providing said third port is adapted for convenience in machining or otherwise suitably finishing the surface of the plate around the port, 33, to make a fluid-tight junction with the terminal of the suction conduit as hereinafter described.

10 A pipe, 40, constituting the suction conduit, which may be understood as leading to the engine intake manifold (not shown) is 15 mounted in fixed position on the top plate, 21, as by means of brackets, 41 and 42, and said suction conduit is provided with a terminal inlet member, 43, which is movably mounted 20 directly over the third port, 33, of the vacuum chamber and movable vertically to carry its inlet port, 44, into and out of junction with said third port, 33, of the vacuum chamber.

25 This suction conduit terminal member, 43, has its vertical duct passage closed at the upper end and open laterally, as seen at the port, 45, at the side of said terminal member at which it makes junction with the fitting, 30 46, provided for connection of the terminal, 43, with the fixedly mounted suction conduit member, 40, having a port, 47, which is lapped by the port, 45, to the full area of the latter port at the position of the terminal, 43, at which the ports, 44 and 33, are in 35 junction. Said fitting, 45, serves also to stop the suction conduit member, 40, against longitudinal displacement, which is effected by abutting said fitting, 45, against the bracket, 32, as seen in Figure 4.

40 The suction conduit terminal, 43, is held in fluid-tight junction with the fitting, 45, by the spring element of a snap action provided for causing the desirably instantaneous shifting of the suction inlet port, 44, of 45 the suction terminal member, 43, into and out of junction with said third port, 33, of the vacuum chamber. This snap action will now be described.

50 At a short distance to the left of the lugs of the third port, 33, a bracket, 50, mounted on the top plate, 21, carries a swivel guide bearing, 51, for the stem, 52, of a forked yoke, 53, in whose fork the suction conduit inlet 55 terminal, 43, is pivotally engaged, and a spring, 55, coiled about the stem, 52, reacts between the swivel guide bearing, 51, and the yoke, 53, stressing the suction conduit terminal, 43, against the fitting, 45, the guide bearing, 51, being at such level that when the stem, 52, of the yoke, 53, is horizontal, that is, at right angles to the seating faces of the terminal, 43, and fitting 45, the inlet port 44 of the terminal, 43, is very nearly down in junction 60 with the third port, 33, of the vacuum cham-

ber, so that very slight movement carrying the stem, 52, very slightly below horizontal position, seats the terminal, 43, fluid-tight on the plate, 34, of the vacuum chamber. And upon upward thrust of the terminal carrying the stem, 52, past horizontal position, the reaction of the snap spring quickly completes its upward movement for separating the lower end of the terminal, 43, and the inlet port, 44, thereof, from the third port, 33, of the chamber, so that the two ports, 44 and 33, are effectively out of junction with each other, being so far separated that no suction is communicated to the vacuum chamber from the suction conduit, but instead, the suction operating through that conduit, draws in air and vapor from the space 59 above the vacuum chamber which is made effectively a continuation of the fuel accumulating chamber by means of a cover, 60, said space being, however, for convenience of identification, referred to as a third chamber.

70 The flange, 61, of a cover, 60, is dimensioned for fitting snugly, but not necessarily airtight, about the upper end of the shell, B, 75 of the accumulating chamber, said flange being notched, as seen at 62 and 63, to accommodate the elbow, 28, and the fixed suction conduit member, 40.

75 This cover thus completes the enclosure of 80 the third chamber, 59, which is in free communication with the accumulating chamber, A, but is distinguished from the latter by the fact that the fuel will not normally accumulate above the level at which in the operation of the device as hereinafter described, 85 the float, hereinafter mentioned, rising with the liquid, separates the suction conduit terminal and inlet port from the third port, 33, of the vacuum chamber; and therefore 90 liquid will not normally occupy the space, 59, which is accordingly distinguished from the accumulating chamber as constituting a third chamber.

95 It will be understood that for desired rapid 100 action to give the apparatus the desired capacity for pumping fuel to the engine served, the atmosphere access to the vacuum chamber should be more free than will be afforded by a port no larger than it is practicable to make 105 the suction inlet port; and accordingly, as shown, the third port, 33, of the vacuum chamber, which is the atmosphere inlet port, 110 as well as the port of access of suction when the suction inlet port is in junction with it, 115 is shown several times the area of the suction inlet.

120 It has been observed in the operation of 125 fuel feeding devices of the character commonly called vacuum tanks which have the suction access closed during the emptying phase of the tank that some disturbance of the fuel mixture may result from air flow into the intake manifold during the filling phase which is interrupted in the emptying phase. 130

This embarrassment is designed to be minimized, and under some running conditions may be entirely obviated, by the construction shown, in which it will be observed that the intake manifold uninterruptedly derives from the vacuum tank air mixed more or less with fluid vapor, the mixture being taken from above the fuel in the vacuum chamber during the filling phase of the tank, and from the 5 third chamber, and thus from above the fuel in the accumulating chamber, in the emptying phase. Under some circumstances, when the vacuum tank is somewhat heated by reason of its proximity to the engine, the mixture 10 thus derived may be found so approximately uniform in respect to proportion of air and fuel vapor, that it may be definitely taken into account in the adjustment of the carburetor, and thereby all embarrassment from 15 disturbance of the mixture may be avoided. 20 In view of the circumstance that in the filling phase, while the air is drawn from the vacuum chamber against the resistance due to the degree of vacuum developed in the chamber for 25 lifting the fuel, and which is measured by the fuel lift, the quantity of the air and fuel vapor mixture taken into the manifold will usually be less than while it is drawn from the third chamber, which is always at atmos- 30pheric pressure.

And in order to provide for equalizing these two quantities, provision is made for restricting the access to the suction conduit during the emptying phase relatively to the 35 access during the filling phase. This provision consists in an adjustable stop screw, 47, mounted in the fitting, 45, and accessible for adjustment through an aperture, 64, in the cover, said aperture serving also as an atmosphere vent for the third chamber. The 40 screw at the lowest adjustment will stop the terminal, 43, in the movement for separating the ports, 44 and 33, at position of complete lap of the ports, 46 and 47; and when it is 45 desired to restrict the suction access during the emptying phase, the screw will be adjusted by slight withdrawal, so that the snap action will carry the terminal a little farther, and reduce the lap of the ports to restrict the 50 air and fuel vapor access to the desired degree for equalizing the quantity flow, in view of the difference in the resistance mentioned.

This creates liability of the suction hold on the suction conduit terminal being great 55 enough under condition of high degree of vacuum in the intake manifold, to require a float of inconvenient size in order to have buoyant value adequate for breaking the suction hold when the float is operating to separate the inlet port from the third port, for 60 putting the chamber in communication with the atmosphere instead of with the suction.

To obviate this difficulty, and make the apparatus operable with a conveniently small 65 float, the top plate, 21, of the vacuum chamber

is provided with a movable part occupying and closing an aperture, 36, made in the top plate for that purpose, said movable part becoming thus a part of the top wall of the chamber and being movable inwardly and 70 outwardly with respect to the chamber cavity without opening the wall at said aperture. As shown, this movable wall member is a flexible diaphragm, 70, mounted for closing a round hole, 71, made in the plate, 21, the 75 diaphragm being clamped liquid-tight on the margin of said hole by any convenient means, as an annular clamp, 72; and a lever of the first class, as indicated at 75, is connected at one end to said diaphragm, 70, at the center 80 of the latter, the other arm of the lever being extended for engagement with an abutment, 77, provided on the suction conduit terminal, 43, at a position for encounter of the lower end with said abutment in the movement of 85 the terminal into junction of the inlet port, 44, with the third port, 33, of the vacuum chamber.

The parts are dimensioned and positioned to cause the diaphragm to be slightly flexed 90 outwardly with respect to the chamber by such encounter, and the completion of the movement of the suction conduit terminal into full junction of the ports, 44 and 33.

The operation of this construction, it may 95 be understood, is, that the suction hold on the terminal, 43, due to vacuum in the vacuum chamber, is offset by like action of the vacuum on the diaphragm, 70; and by making the diaphragm with its flexible,—and thereby mov- 100 able,—part, of an area substantially equal to the area on which the suction operates for holding the terminal, 43, seated on the steel plate, 34, which contains the port, 33, the suc- 105 tion hold is counterbalanced by the suction on the diaphragm; and the float need be only large enough to give it buoyant value ade- 110 quate to overcome the force of the snap spring operating to hold the terminal, 43, seated in position for junction of the suction inlet and the third port of the vacuum chamber.

I claim:

I. In an apparatus for the purpose indicated comprising a vacuum chamber closed except as to the parts hereinafter mentioned; 115 a liquid accumulating chamber having limited atmosphere vent at the top, and a third chamber over the vacuum chamber in free atmospheric communication with the accum- 120ulating chamber, the vacuum chamber having at upper and lower parts thereof respectively, a liquid inflow port and a liquid discharge port having respectively liquid supply connection for deriving supply from a source of liquid, and liquid discharge connection for 125 delivering liquid to the accumulating chamber, the vacuum chamber having at the upper part a third port opening into said third chamber; a suction conduit arranged for connection with a source of suction, said suc- 130

- tion conduit being mounted in said third chamber and comprising a terminal having an inlet port, said terminal being mounted for movement to carry said inlet port into and out of junction with the third port of the vacuum chamber; a float in the vacuum chamber, and means operated by the float for moving said terminal to carry its said inlet port into and out of junction with said third port of the vacuum chamber upon the descent and rise of the float due to the fall and rise of the level of the liquid content of the vacuum chamber to predetermined limits.
2. The construction defined in claim 1, having the vacuum chamber connected for supply with a source of liquid fuel, and a suction conduit leading to the intake manifold of the engine, whereby the engine derives air more or less charged with fuel vapor both from above the fuel in the vacuum chamber and also from above the fuel in the accumulating chamber.
3. The construction defined in claim 1, the suction conduit terminal having its suction inlet port slidingly associated with the adjoining part of said conduit, the adjoining ends of said slidingly associated parts of the conduit having their co-operating ports arranged to lap to a predetermined area at the position of junction of the suction inlet port with the vacuum chamber third port, and adjustable means for stopping the movement of said suction conduit terminal adapted to be adjusted to cause said co-operating ports to lap to less extent at the position of separation of said inlet port and third port.
4. In an apparatus for the purpose indicated, a chamber having a liquid inlet port and a liquid outlet port, and having a third port at the upper part; a suction conduit arranged for connection with a source of suction and having a terminal member with a suction inlet port, said suction conduit terminal being mounted movably on the chamber; means arranged to be operated by change of level of the liquid content of the chamber associated with said movable suction conduit terminal for moving the inlet port of the latter into and out of junction with said third port of the chamber at predetermined high and low levels respectively of said liquid content, said suction conduit terminal being slidingly associated with the adjoining part of said conduit, the adjoining ends of said slidingly associated parts having their co-operating ports arranged to lap over a predetermined area at the position of junction of the suction inlet port with the vacuum chamber third port, and adjustable means for stopping the movement of the suction conduit terminal away from said junction position, arranged to be adjusted to limit said movement at a position at which said co-operating ports lap to less than said predetermined area.
5. In an apparatus for the purpose indicated, a chamber having a liquid inlet port and a liquid outlet port, and having a third port at the upper part; a suction conduit arranged for connection with a source of suction, and having a terminal member with a suction inlet port, said suction conduit terminal being mounted movably on the chamber; means arranged to be operated by change of level of the liquid content of the chamber associated with said movable suction conduit terminal for moving the inlet port of the latter into and out of junction with said third port of the chamber at predetermined low and high levels respectively of said liquid content, said chamber having a limited portion of its wall movable without opening the wall, and operating connections between said movable wall member and said suction conduit terminal for applying the movement of the former due to vacuum in the chamber, to said movable wall member in the direction for separating the suction inlet port from said third port of the chamber.
6. In the construction defined in claim 5, the area of said movable wall member corresponding to the area of said third port in the approximate degree necessary for causing the suction pull of said movable wall member inwardly with respect to the chamber to equalize the suction hold on the suction conduit terminal due to vacuum in the chamber.
7. In the construction defined in claim 5, the area of said movable wall member corresponding to the area of said third port in the approximate degree necessary for causing the suction pull of said movable wall member inwardly with respect to the chamber to equalize the suction hold on the suction conduit terminal due to vacuum in the chamber, and a snap action device arranged for acting on said movable suction conduit terminal for yieldingly resisting the initial part of its movement in direction for separating the suction inlet port and the chamber third port.
- In testimony whereof, I have hereunto set my hand at Chicago, Illinois, this 22nd day of October, 1929.
- CHARLES S. BURTON.
